UNITED STATES PATENT OFFICE.

FRANK W. MERRICK, OF BOSTON, MASSACHUSETTS, ASSIGNOR TO UNITED SHOE MACHINERY CORPORATION, OF PATERSON, NEW JERSEY, A CORPORATION OF NEW JERSEY.

LEATHER-EDGE-FINISHING MACHINE.

Application filed December 14, 1920. Serial No. 430,618.

This invention relates to finishing machines and is herein illustrated as embodied in a machine for burnishing the edges of pieces of upper leather.

5 It is desirable to apply to the edge of the leather during the burnishing operation a finishing substance which may act to color the edge, to coat it, to impart lustre to it or to accomplish any or all of these ends. Such 10 substances vary in consistence from thin liquids, such as stains, to viscous liquids such as solutions of celluloid. According to one feature of the present invention there is provided an edge finishing tool past which the 15 material is fed in such manner that the tool rubs the edge progressively, and a force feed for delivering finishing substance close to the locality at which the tool operates. In the 20 illustrative machine the edge of the material is supported upon and fed by a rotating material-support in the form of an annulus, the material being advanced by the annulus and guided into proper position with respect to a rotary burnishing tool by a gage which 25 engages the edge of the material just in advance of the tool, a conduit for the finishing substance being provided which leads out through the operative face of the edge gage and has extending into it a plunger which 30 may be reciprocated to force finishing substance upon the edge of the material.

Finishing substances should not be exposed to the air any more than is necessary, and their delivery should be restricted to the 35 edge of the material. According to another feature of the invention, means are provided for starting and stopping the delivery and for minimizing the exposure of the supply to the atmosphere. In the illustrated machine, the plunger which controls and aids such delivery normally maintains the conduit closed but is operated to cause continuous delivery of the substance during the 40 time that material to be operated upon is in the machine, its operation ceasing as soon as the material has passed through the machine.

45 These and other features of the invention including certain details of construction and combinations of parts will be described as embodied in an illustrative machine and pointed out in the appended claims.

50 Referring now to the accompanying drawings,

Fig. 1 of the drawings is a front view of

the illustrative embodiment aforesaid of the 55 features of the invention.

Fig. 2 is a side elevation of the machine shown in Fig. 1, the stationary work table 5 being omitted.

Fig. 3 is a plan view thereof, the container for the finishing substance or preparation being omitted.

Fig. 4 is a sectional view showing the parts at the rear of line 4, 4, in Fig. 3.

Fig. 5, Sheet 1, is a partly sectional view 65 showing the rotary tool and parts immediately adjacent thereto.

Fig. 6, Sheet 1, is a view of the same parts as Fig. 5, looking from the left hand side 70 in the latter figure.

Fig. 7, Sheet 1, is a view showing the tool and certain parts adjacent thereto, mostly in vertical section.

Fig. 8, Sheet 2, shows the cam-actuated 75 bell-crank or rocker separately.

Fig. 9, Sheet 2, is a partly sectional detail view showing the relations between the said bell-crank or rocker and the rotating actuating cam.

Fig. 10, Sheet 2, is a detail view in plan 80 showing a portion of the countershaft, with its cam, and the supporting means for the countershaft.

Figs. 11 and 12, Sheet 4, respectively are a side elevation and plan of a portion of the 85 annulus, the tool, and associated parts.

The machine shown in the drawings resem- 90 sables that of the Letters Patent No. 1,339,776 in that it contains a rotary burnish- 95 ing tool 20, a work-backing and feeding an- nulus 10, and a presser-wheel or hold-down 40. It contains also a stationary work-table 5 like that of the former Letters Patent, such work-table being omitted from Fig. 2 hereof. These elements perform functions 95 similar to those of the corresponding parts in the machine shown and described in such Letters Patent. That is to say, the annulus 10, occupies and turns in a plane which as shown best in Fig. 1 is slightly inclined 100 away from right angles with the plane of rotation of the burnishing tool 20; it supports by its upturned, slightly conical, working face the marginal portion of a piece of leather lying upon it and the work-table 5; 105 and it backs up such portion against the pressure of the presser-wheel while being operated upon by the tool, and by its rota-

tion feeds the said marginal portion to and past the tool. The presser-wheel or hold-down 40 holds the leather in firm contact with the working face of the annulus 10, 5 keeps it from displacement while being acted upon by the tool 20, and facilitates the feeding of the leather by the annulus. The rotary tool 20 in this instance, as in the said Letters Patent, condenses and shapes the 10 marginal portion and edge of the leather, and burnishes the said portion and the edge.

The transversely extending shaft 21 with which the tool 20 is connected is mounted in 15 bearings in a fixed frame-part 22. The shaft and tool in this instance are rotated by means of a small band-pulley 23, fast on the shaft, receiving a driving-band 24 from a large band-pulley 25 fast on a countershaft 20 d mounted in bearings d¹, d², at the rear of the machine. The said countershaft is shown provided with fast and loose pulleys d³, d⁴, for the reception of a driving-band (not shown) by means of which the said 25 countershaft is driven when required. Fig. 7, Sheet 1, shows the tool 20 in detachable screw-threaded connection with the shaft 21.

The substantially upright, slightly inclined, shaft with which annulus 10 is connected is journaled in bearings in connection with a carrier 10^a that is applied to one end of a mounting 10^b. The said mounting is supported in place substantially as in the prior Letters Patent, namely by having an upwardly projecting portion 10^c of the opposite end of the same pivotally engaged with center-screws 11, 11, carried by the upper portions of uprights 12^a, 12^b, the latter in this instance rising from the machine bed-plate 12. The driving connections by which annulus 10 is rotated, for the purpose of feeding the material to be operated upon through the machine, are similar to those of the prior Letters Patent, namely comprising a bevel gear 10^d upon the upright or substantially upright shaft of the annulus, a bevel pinion 10^e engaging said bevel gear, a transversely extending shaft having said bevel pinion fixed upon its left hand end, and a band-pulley 10^f upon the right hand end of the said shaft adapted to receive a suitable driving band.

The application of a coloring or finishing substance or preparation to the material operated upon by the tool is provided for in the present instance by means of a conduit having an outlet suitably disposed with relation to the path of the said material. As shown best in Figs. 5 and 6, Sheet 1, the conduit is a passage a formed in a casing a² surrounding the cylindrical hub of the tool, (see Fig. 7, Sheet 1), said passage inclining downward to an outlet a', as indicated in Figs. 5 and 6, in the end-surface of the said casing in close proximity to the point where

the tool touches the material, and located just above the inner margin of the annulus 10. The end-casing extends to the position of the tool, and the said end-surface constitutes a guide or gauge for the edge of the material, which is one of the features included in the present invention, so that the said edge bears against such end-surface as the material is fed to the tool. Consequently the edge receives the coloring or finishing substance or preparation from the outlet in being thus fed. The requisite supply of the said substance or preparation is furnished by means of a suitable filled reservoir or container, such for instance as that shown by b, Figs. 1 and 2, (but omitted from Fig. 3) having its discharging nozzle b' entered into a chamber a⁴, Fig. 5, in casing a². The passage a intersects the said chamber, so that the coloring or finishing substance or preparation received within the chamber from the container may enter the passage. The container b is detachably applied to casing a², so that it may be removed when desired, and in practice I provide a number of containers containing solutions or preparations of different colors, the different containers being interchangeably employed to suit the special requirements of the work.

Although supply and feeding means of various known kinds may be employed in practice, I prefer to employ mechanical means for ensuring feed of the said substance or preparation in properly proportioned quantity, and may adopt any of various forms of force feed devices suitable for the purpose. The illustrated machine contains a preferred form of means of such class, comprising a needle-plunger c which occupies the passage a and is given endwise reciprocating movements therein. In such movements the plunger causes, or assists in causing, the coloring or finishing substance or preparation to issue at the outlet a', and in addition prevents clogging of the passage and outlet. The means of imparting the reciprocating movements to the plunger c may be varied in practice. Herein, the said means comprises a rotating cam c⁶ on the countershaft d at the rear of the machine, and connections between the plunger and the said cam. Such connections consist in this particular instance of a plunger carrying block c⁷, a bell-crank c⁸ mounted by a pivot c⁹, Figs. 2 and 3, upon a stationary bracket c¹⁰ adjacent the tool 20, and having the plunger-carrying block c⁷ connected therewith by a pivot c¹¹, Figs. 2 and 6, a rod c¹² having one end thereof connected to such bell-crank, and a second bell-crank or rocker, c¹³, at the rear of the machine having an upstanding arm to which the other end of the said rod is connected, and a horizontal arm extending rearwardly beneath

cam c^6 and furnished with a rib c^8 shown best in Fig. 8, Sheet 2, against which said cam acts. The said bell-crank or rocker c^5 is mounted between center-screws c^{50} , c^{50} , in connection with upstanding supports c^{51} , c^{51} , and is adapted to swing in a vertical or substantially vertical plane, in the direction from front to rear of the machine and vice versa. A spring c^4 , Figs. 2 and 3, acts upon it oppositely with respect to the said cam to keep the rib c^8 in contact with the cam or the adjacent portion of the shaft d . It rocks in the said vertical plane upon said center-screws c^{50} , c^{50} , when actuated by the cam and spring, and by means of the rod c^4 transmits movement to the bell-crank c^2 so as to swing the latter and thereby cause the plunger c to reciprocate endwise within the passage a .

Preferably, the devices for ensuring feed of the coloring or finishing substance or preparation are contrived to operate as a force feed, and the retracting movement of the plunger c is made sufficient in extent to withdraw its leading end into the chamber a^4 so as to afford opportunity for the said substance or preparation to flow from the chamber into the portion of passage extending from the chamber to outlet a' . In the projecting stroke of the needle-plunger, its leading end forces a small quantity of the coloring or finishing substance or preparation ahead of it through the said portion of the passage a , to the outlet a' , said end reaching in such stroke a point close to the position of the edge of the material operated upon. This action causes the said quantity of the said substance or preparation to be delivered to the said edge closely adjacent the point at which the latter is subjected to the action of the tool.

The reciprocating action of the needle-plunger takes place with such rapidity that a continuous supply of the coloring or finishing substance or preparation is ensured at the outlet a' .

The use of a reciprocating needle-plunger is especially advantageous when employing a viscous quickly hardening substance or preparation, such as a solution of celluloid in amyl-acetate. The said device ensures a regulated feed at the outlet a' and prevents the passage a and the said outlet from becoming clogged.

The avoidance of waste of the fluid substance or preparation employed is attained in the illustrative machine through providing for control of the feeding of the said substance or preparation so that no feeding thereof shall take place in the absence of material to be operated upon, and so that feeding shall begin when a piece of such material is in position to receive such substance or preparation, shall continue while the said piece is in such position, and shall

suspend when the piece has passed from such position. This control is of great importance in a machine employed for operating upon separate pieces of leather designed to form parts of shoes. In the illustrated machine I utilize for the said control a detector constituted by a member which itself is controlled by the piece of material inserted into the machine. Such member is in this instance the presser or hold-down 40, although in some cases it may be another piece specially employed as a detector. The presser 40 is movably supported in the machine by means of a presser-carrier 41 supported by a mounting 41^a, Figs. 1 and 2, that is pivoted by means of center-screws, 42, 42, upon the fixed frame-part 22 with capacity to swing in a vertical plane so as to allow the presser to move to accommodate itself to the material when the leading end of the latter is inserted under the presser, and so as to provide for downward movement of the presser when the material passes out from under the presser. A contracting coiled spring 43, Fig. 1, connected with the presser-carrier holds the presser-carrier and presser toward the surface of annulus 10, yields to permit the presser to be separated from the said surface by the entrance of a piece of material between the two, and draws the presser toward the said surface when the material passes out from under the presser. The position of the presser or other detecting member determines whether there shall be feeding of the coloring or finishing substance or preparation, or the feeding shall be suspended. In practice, various arrangements may be employed for causing the feeding to begin when the presser is separated from the annulus, continue while the pressure remains separated from the annulus, and cease when the presser moves toward the annulus again. Herein such action is provided for by mounting the bell-crank or rocker c^5 upon a laterally-movable carrier constituted by an upright arm c^{52} . The said carrier arm is made laterally movable by being pivoted between center-screws c^{53} , c^{53} , on a supporting carriage C, and its lateral movements taking place under the control of the presser or other detector are adapted to place the bell-crank or rocker either in working relations with the cam c^6 or out of working relations with the latter. Normally, the carrier-arm is caused by the tension of a contracting coiled spring m , Figs. 1 and 4, to occupy a position toward the right-hand side in Figs. 1, 3 and 4, in which it presents the rib c^8 , (Fig. 8) of the horizontal arm of bell-crank or rocker c^5 to a concentric or substantially concentric portion of the cam c^6 or rotating shaft d as in Fig. 4. So long as the parts occupy the position just referred to, the bell-crank or rocker is out of working relations

with the cam c^6 , and the plunger c is not actuated to feed the coloring or finishing substance or preparation.

In this relation of the parts, the plunger occupies the portion of passage a which is adjacent outlet a' and, acting as a valve, closes the passage so as to prevent outflow of the said substance or preparation. Movement of the carrier-arm c^{52} toward the left from its position in the drawings will place the bell-crank or rocker in working relations with the cam and result in actuation of the plunger to feed the said substance or preparation.

An electro-magnetic arrangement is employed in the present instance to control the relations between bell-crank c^5 and the rotating cam c^6 , the devices being so contrived and combined that the movements of the presser and presser-carrier from one position to another, or vice versa, are made to close or open, as the case may be, an electric circuit embracing an electro-magnet g , which more immediately effects the said control. Thus, an arm h projecting from the presser-carrier 41 is furnished with an insulated contact-point h' constituting one of the terminals of the said electric circuit, a second insulated contact-point h^2 being mounted in fixed position upon a stand or bracket h^3 supported by a fixed part of the machine. The wiring h^4 , h^5 , of said circuit is shown, for convenience, connected with a plug h^6 applied to a socket h^7 having a key h^8 and connected with the wires h^9 communicating with a source of electric energy. Key h^8 serves in usual manner for turning the current on and off at the socket. During use of the machine the current ordinarily will be turned on by means of the said key. So long as the presser occupies a position close to the surface of the annulus the contact-points h' , h^2 , remain separated, with the circuit open or broken and the electro-magnet inert; when the presser is separated from the annulus by material inserted between them the contact-points are brought together, the electric circuit is closed, and the electro-magnet is energized. For cooperation with the magnet, an armature k is attached to the laterally movable upright arm c^{52} . When the insertion of a piece of material to be operated upon by the tool separates the presser from the annulus, the bringing together of the contact-points closes the electric circuit and causes the electro-magnet to be energized. The magnet through its attraction for the armature draws the latter and the carrier-arm c^{52} toward the left so as to move the bell-crank or rocker c^5 into position to be acted upon by a portion of cam c^6 of sufficient eccentricity or throw to produce feeding actuation of the needle-plunger, and the resulting feeding of the coloring or finishing substance or preparation continues until the piece of material passes out from

under the presser. This permits separation of the contact-points to take place, with resulting de-energizing of the magnet, allowing the spring m to move arm c^{52} toward the right and thereby transfer the bell-crank or rocker c^5 to the concentric or substantially concentric part of the cam or shaft again, thus suspending the actuation of the needle-plunger.

To facilitate the lateral movement of the bell-crank or rocker c^5 from its idle position in Fig. 4, at the right of the cam c^6 toward the left into a position in which a high or eccentric portion of the cam will act thereon, the said high or eccentric portion is located at one side of the shaft d , the opposite side of the said shaft (or of a sleeve on which the cam is formed) being concentric with the shaft axis. When the magnet acts to produce such lateral movement, the horizontal arm of bell-crank or rocker c^5 will pass unobstructedly along this concentric portion as the latter is presented to the said arm by the revolution of the shaft.

The movement of the arm c^{52} toward the right under the pull of the spring m is limited by a fixed stop, n , Figs. 1 and 4, which, as indicated in Fig. 4, determines the location of the idle position of the bell-crank or rocker c^5 laterally with relation to the cam c^6 . To enable the said position to be adjusted and corrected if required, the said stop is made as an adjustment screw, occupying a threaded hole tapped in an upright arm n' rising from the right hand side of the carriage C which supports the electro-magnet and the carrier arm c^{52} .

Adjustability of the feeding means for the coloring or finishing substance or preparation, for enabling the rate at which the latter is fed to be varied at will, is provided for in this instance by constructing the actuating means for the plunger c with capacity for variation of the stroke of the plunger. Herein such capacity is secured by constructing the rotating cam c^6 with portions of varying eccentricity or throw, and making the bell-crank or rocker c^5 capable of being placed in working relations with the portion which will produce a stroke giving the rate of feed that is required. With the parts constructed and combined as in the illustrated machine, the greater the eccentricity of the cam-portion, which actuates the bell-crank or rocker, the farther the needle-plunger c will be withdrawn from outlet a' and back within the chamber a^4 , and vice versa. Preferably, the said cam c^6 is made of gradually increasing eccentricity or throw from right to left, and by regulating the distance that the bell-crank or rocker c^5 is carried toward the left from its idle position at the right of the cam in being called into action, so as thereby to place it in position to be acted upon by a

cam-portion of the proper eccentricity or throw, the desired length of stroke is secured. This regulation is effected herein by shifting the acting end of the core of the 5 electro-magnet g in the required direction, so that when the armature k has been attracted by the energized magnet and moved toward the latter, accompanied by upstanding arm c^5 and bell-crank or rocker c^6 , this action 10 will carry the bell-crank or rocker either farther lengthwise of the cam or not so far, as the case may be, and thereby place the horizontal arm of the bell-crank or rocker in working relations with the portion of 15 the cam which will give such length of stroke. Compensating adjustment of stop n will be made, if necessary, to permit the spring m to return the bell-crank or rocker back to the portion of least throw of the 20 cam, or the concentric portion of the cam or of the shaft d . This shift of the acting end of the core of the electro-magnet is provided for in the present instance by making carriage C adjustable transversely of the 25 machine, so that by such adjustment of the carriage the electro-magnet in its entirety embracing the core is thus shifted. Herein, the said carriage is pivoted by means of a screw C^x to bed-plate 12 so as to adapt it to 30 be swung transversely about such screw. An arm C^y of the carriage is extended to the front of the machine to serve as a convenient handle that may be used by the operator for 35 swinging the carriage in making required adjustments of the character just explained.

I provide for varying the point reached by the plunger in its down stroke. That is to say, the closeness of approach of the end of the plunger to the outlet. In the 40 present instance the rod c^4 is made adjustable lengthwise. Its rear end occupies a hole through a connection-piece c^{41} that is pivotally connected to the upstanding arm of bell-crank or rocker c^6 . After loosening the 45 binder-screw c^{42} , Fig. 2, which fastens the rod c^4 to the connection-piece, the rod may be shifted lengthwise to the necessary extent and then be secured in the position of relative adjustment thereby attained by 50 tightening up the said binding screw.

Referring now to annulus 10: The mounting 10^b and annulus in this instance are 55 yieldingly upheld by a spring 13, Fig. 1, upon which the intermediate portion of the mounting rests. The lower blade or leaf of the said spring rests upon a nut 13^a upon a threaded stem 13^b rising from the bed-plate 12. Through adjustment of the nut up or down upon the said threaded stem, the tension of the spring, and thereby the resistance which the annulus offers to being depressed by work entering between it and the tool 20, may be regulated; and thereby the 60 degree of the force with which the work is held in contact with the tool, and the effect

produced by the tool upon the work, may be regulated. The spring may be omitted if desired, as in the prior Letters Patent, and the nut alone be utilized to adjust the mounting and annulus up or down. 70

As a means of adjusting the closeness of approach of the working surface of the annulus 10 to the tool, to suit different thicknesses of stock operated upon and vary the results secured upon the stock, I have provided the illustrated machine with an adjusting screw t , Fig. 1, applied in connection with a fixed portion of the machine-frame, said screw being arranged horizontally and having a conical end which engages with the 80 upper side of an end portion of the mounting 10^b for the annulus. The action of spring 13, in pressing the mounting upward so as to keep the annulus up close beneath the tool, keeps the said end-portion of the 85 mounting in contact with the said conical end of the adjustment-screw. Such conical end constitutes a stop which defines the closeness of approach of the working surface of the annulus to the tool. Adjustment 90 of the screw endwise varies the said closeness of approach, according as larger portions of the cone are presented in position for the end-portion of mounting 10^b to engage therewith or are withdrawn so that 95 smaller portions of the cone are presented in such position.

I provide for preventing portions of the material operated upon from being carried down at the inner periphery of annulus 10 100 by the action of the tool 20, so as to produce a feather edge, by mounting the annulus so that it shall be movable toward the guide or gauge for the material-edge, and causing the said inner periphery to bear against the said guide or gauge and extend across the radial face, 20^a , of the tool, close to the said face. As described earlier herein, the edge-guide or gauge is constituted by the end-surface of the casing a^2 adjoining the tool. It surrounds the periphery of 105 the radial face 20^a of the tool. The said movability of the annulus is secured by providing for movement of annulus-carrier 10^a 110 transversely, in the present instance by pivoting foot of the annulus-carrier by means of center-screws s , Fig. 1, to the said mounting, and herein the inner periphery of the annulus is caused to bear against the said end-surface by the tension of a contracting coiled spring s' which is engaged with the annulus-carrier. The casing a^2 is mounted upon the free end of the fixed frame-part 115 22 through which the tool-shaft extends. It is fixed adjustably in its working position by convenient means for the purpose. Herein a clamping screw a^{21} , Fig. 5, is employed. In practice the said casing is adjusted laterally into a position in which it holds the 120 inner periphery of the annulus just clear 125 130

of the radial face 20^a of the tool. The setting is so close, without actual contact of the said inner periphery with face 20^a, as to prevent portions of the edge of the leather from being carried down by the face, between it and the inner periphery of the annulus.

For convenience in cleaning, when necessary, I provide for enabling the presser 40 and the portion of the presser-carrier 41 on which it is mounted to be turned forward away from proximity to the tool. Thus I construct the presser-carrier in two parts, one thereof, 41^a, a mounting for the other, and I connect the arm-portion of the presser-carrier with the said mounting portion by means of a pivotal screw 41^b, Fig. 1. This pivotal connection enables the arm-portion to be swung forward, with the presser 40, after the removal of the container *b* and its discharging nozzle *b'*.

What is claimed as the invention is,—

1. The combination with an edge-finishing tool, of means for feeding coloring or finishing substance or preparation for application to the edge face of the material which is operated upon in advance of the tool itself, controlled by the material and operating to feed in the presence of the material and suspend the feeding in the absence of the material.

2. The combination with an edge-finishing tool, of means for feeding coloring or finishing substance or preparation directly to the edge face of the material which is operated upon in advance of the tool itself, controlled by the material subjected to the action of said tool and operating to feed during the presence of such material and suspend feeding in its absence.

3. The combination with means for advancing material to be operated upon, of means for feeding a fluid substance or preparation to said material, controlled by such material and operating to feed the said substance or preparation continuously during the presence of the material and suspend such feeding in its absence.

4. The combination with a finishing tool, a moving member which serves both as a supporting and a feeding means while the material is being operated upon by the tool, and a presser or hold-down cooperating with said member, of means independent of the presser for feeding coloring or finishing substance or preparation, controlled by the material through the said presser or hold-down and operating to feed said substance or preparation while the presser or hold-down is lifted by the material and suspend such feeding in absence of the material.

5. The combination of a rotary burnishing tool, means for feeding a fluid substance or preparation, to the material operated upon in advance of said tool, and detector means

controlled by the said material and controlling the said feeding to cause the latter to occur while the material is in position, and suspend the feeding in the absence of the material.

6. The combination with a rotary edge-finishing tool, a moving surface which supports the material while being operated upon by the tool and advances it, and a presser or hold-down cooperating with said surface, of means independent of the presser for feeding coloring or finishing substance or preparation to the material edge, controlled by the material through the said presser or hold-down and operating to feed said substance or preparation while the presser or hold-down is lifted by the material and suspend such feeding in absence of the material.

7. A machine for applying a finishing substance to the edge face of a piece of upper leather and for burnishing said edge face having in combination a burnishing tool, a conduit for delivering finishing substance directly to said edge face and a device independent of the tool for mechanically aiding the delivery of said substance through said conduit to said edge face.

8. The combination with an edge-finishing tool, of a conduit delivering a coloring or finishing substance or preparation directly to the edge face of the material, and a plunger reciprocating endwise in said conduit.

9. The combination of means comprising a conduit delivering fluid substance or preparation to material to be operated upon, a needle in said conduit, and actuating means for said needle, controlled by the said material, reciprocating said needle during the presence of the material, and suspending its movements in the absence of material.

10. The combination of means comprising a conduit delivering fluid substance or preparation to material to be operated upon, a plunger in said conduit, and actuating means for said plunger, controlled by the said material, reciprocating said plunger during the presence of the material, and suspending its movements in the absence of material.

11. The combination with an edge-finishing tool, of means comprising a conduit delivering a coloring or finishing substance or preparation to the edge face of the material, a plunger in said conduit, and actuating means for said plunger controlled by the material, reciprocating said plunger during the presence of the material, and suspending its movements in the absence of the material.

12. The combination of a presser engaging with material to be operated upon, means comprising a conduit delivering coloring or finishing substance or preparation to the said material, a needle-plunger working in said conduit, and actuating means for said needle-plunger controlled by the material through the presser, reciprocating the needle-plunger

during the presence of the material, and suspending its movements in the absence of the material.

13. The combination of a conduit which supplies fluid substance or preparation to material being operated upon, a plunger working in said conduit, and plunger-actuating devices controlled by the material operated upon, actuating the plunger while the material is in position, and in the absence of the material suspending said actuation with the plunger in position to close the conduit.

14. The combination of a conduit for delivering fluid substance or preparation for application to material to be operated upon, a plunger working in said conduit, a cam-actuated member with which the plunger is operatively combined, an actuating cam, and means acting under control of the material operated upon to render said member and the cam operative to actuate the plunger when the material is in position and inoperative to actuate it in the absence of the material.

15. The combination of a conduit for delivering fluid substance or preparation for application to material to be operated upon, a plunger working in said conduit, a cam-actuated member with which the plunger is operatively combined, an actuating cam, and means acting under control of the material operated upon to produce relative lateral movement between said member and said cam and thereby establish working relations between them when the material is in position and disestablish such relations in the absence of the material.

16. The combination of a conduit for delivering a fluid substance or preparation for application to material to be operated upon, means for feeding the said substance or preparation through the said conduit, and electro-magnet devices for controlling the working of said feeding means, themselves controlled by the said material to bring about feeding action when the material is in position and suspend the feeding action in the absence of the material.

17. The combination of a conduit for delivering a fluid substance or preparation for application to material to be operated upon, means for feeding the said substance or preparation through said conduit embracing a cam-actuated member and an actuating cam, and electro-magnet devices acting under control of the material operated upon to produce relative lateral movement between said member and said cam and thereby establish working relations between them when the material is in position and disestablish such relations in the absence of the material.

18. The combination of a conduit for delivering a fluid substance or preparation to

material being operated upon, means for feeding the said substance or preparation through the said conduit, and electro-magnet devices for controlling the working of said feeding means, said electro-magnet devices themselves controlled by the material operated upon to bring about feeding action when the material is in position and suspend the feeding action in the absence of the material.

19. The combination of a conduit for delivering a fluid substance or preparation to material being operated upon, a plunger and actuating means therefor for feeding the said substance or preparation through said conduit, said actuating means embracing a cam-actuated member and an actuating cam, and electro-magnet devices acting under control of the material operated upon to produce relative lateral movement between said member and said cam and thereby establish working relations between them when the material is in position, and disestablish such relations in the absence of the material.

20. The combination of a conduit for delivering a fluid substance or preparation to material being operated upon, a plunger and actuating means therefor for feeding said substance or preparation through said conduit, said actuating means embracing a cam-actuated member and an actuating cam, a support for said member normally occupying a position with such member out of operative relations with the cam, and means acting under control of the material operated upon to produce movement of said support placing said member in working relations with the cam when the material is in position and providing for disestablishment of such relations in the absence of the material.

21. The combination of a conduit for delivering a fluid substance or preparation to material being operated upon, a plunger and actuating means therefor for feeding said substance or preparation through said conduit, said actuating means embracing a cam-actuated member and an actuating cam, a support for said member normally occupying a position with such member out of operative relations with the cam, and electro-magnet devices acting under control of the material operated upon to produce movement of said support placing said member in working relations with the cam when the material is in position and providing for disestablishment of such relations in the absence of the material.

22. The combination of a conduit for delivering a fluid substance or preparation, a plunger for feeding the said substance or preparation through the conduit, a plunger actuating cam of variable throw, and a

cam-actuated member operatively connected with said plunger and adjustable relatively to said cam to vary the rate of feed.

23. The combination of a conduit for delivering a fluid substance or preparation to material being operated upon, a plunger and actuating means therefor for feeding said substance or preparation through said conduit, said actuating means embracing a cam-actuating member and an actuating cam of varying throw, a support for said member normally occupying a position with such member out of operative relations with the cam, means acting under control of the material operated upon to produce movement of said support placing said member in working relations with the cam when the material is in position and out of such relations in the absence of the material, and a carrier for said support, adjustable to vary the relation of said cam-actuated member with respect to said cam and thereby vary the rate of feed of the said substance or preparation.

24. The combination of a conduit for delivering a fluid substance or preparation to material being operated upon, a plunger and actuating means therefor for feeding said substance or preparation through said conduit, said actuating means embracing a cam-actuated member and an actuating cam of varying throw, a support for said member normally occupying a position with such member out of operative relations with the cam, electro-magnet devices acting under control of the material operated upon to produce movement of said support placing said member in working relations with the cam when the material is in position and out of such relations in the absence of the material, and a carrier for said support and the electro-magnet adjustable to vary the relation of said cam-actuated member with respect to said cam and thereby vary the rate of feed of the said substance or preparation.

25. The combination of a finishing tool, a work-gauge or guide, and a conduit for fluid substance or preparation having an outlet in connection with said work-gauge or guide delivering the said substance or preparation to the edge face of the material or work close to the point at which the latter is acted upon by said tool.

26. The combination of a rotary burnishing tool, a work-gauge or guide, and a con-

duit for coloring or finishing substance or preparation having an outlet in connection with said work-gauge or guide delivering the said substance or preparation to the edge face of the material or work close to the point at which the latter is acted upon by said tool.

27. A machine for operating upon the edge face of a piece of sheet material having, in combination, a finishing tool, means for feeding material past the tool in position to have its edge face operated upon, a reservoir for finishing substance and a force feed for delivering the substance to the edge face of the material at a point just in advance of that engaged by the tool.

28. A machine for applying a finishing substance to the edge face of a piece of upper leather and for burnishing said edge face having in combination means for feeding the material past the tool, a conduit arranged to deliver finishing substance directly to the edge face of the leather, a substance-feeding member extending into the conduit, said member being normally at rest, and means capable of being thrown into operation for driving said member.

29. A machine for operating upon the edge of a piece of sheet material having, in combination, a finishing tool, a gage adapted to engage the edge face of the material and guide it to the tool, a conduit for finishing substance having its outlet in the operative face of the edge gage, a member normally extending into the conduit and acting to prevent passage of finishing substance therethrough, and means for operating the member to permit passage of finishing substance and to force the substance through the outlet.

30. A machine for finishing the edge face of a piece of sheet material having, in combination, a finishing tool, mechanism for feeding material past the tool with the edge face of the material in engagement with the tool, means for operating the tool and feed mechanism, a conduit arranged to deliver a finishing substance to the edge face of the material, a substance-feeding member extending into the conduit, said member being normally at rest, and means capable of being thrown into operation to cause said member to be reciprocated by the means which operates the tool and feed mechanism.

In testimony whereof I affix my signature.
FRANK W. MERRICK.
